UNITED STATES PATENT OFFICE.

THOMAS HENRY WASH AND NATHAN ROBERT HODGE WASH, OF MEDINA COUNTY, TEXAS.

CAR-COUPLING.

SPECIFICATION forming part of Letters Patent No. 406,072, dated July 2, 1889.

Application filed March 18, 1889. Serial No. 303,702. (No model.)

To all whom it may concern:

Be it known that we, THOMAS HENRY WASH and NATHAN ROBERT HODGE WASH, citizens of the United States, residing in the county 5 of Medina and State of Texas, have invented new and useful Improvements in Car-Couplings, of which the following is a specification.

Our invention relates to improvements in 10 car-couplings; and it consists in certain novel features hereinafter described and claimed.

In the accompanying drawings, Figure 1 is a perspective view of the end of a car provided with our improved coupling. Fig. 2 is 15 an enlarged side view of the coupling detached and showing the operation of the improvement as two draw-heads are brought together to be coupled. Fig. 3 is a bottom plan view.

20 Our improved coupling is shown as applied to a freight-car A of the usual construction, provided with a draw-head B at its end. The draw-head is that employed in the ordinary pin-and-link coupling, and the pin C is lifted 25 therein, so as to be disengaged from the coupling-link by means of the operating-bar D and lever E, mounted on the end of the car. A spring P is arranged around the operating-bar D and between the upper bearing therof 30 and a shoulder Q thereon. This spring presses the operating-bar downward, so as to prevent the pin jolting out of the draw-head.

To the under side of the car we pivotally 35 secure a forwardly-projecting link-guide support, which consists of the side bars F and the cross-bars G H, connecting the said side bars at intermediate points of their length. The front ends of the side bars are curved downward, as shown, so as to firmly support 40 the link-guide I. This link guide consists of a curved plate provided at its front end with an elongated bearing-loop J J, through which and the ends of the side bars F a pivot-pin K is passed, so as to secure the link-guide to 45 the support. A spring L is arranged between the lower side of the link-guide and the upper side of the cross-bar H and serves to hold the said link-guide normally elevated, so that it will direct the link into the draw-head. 50 This spring also allows the guide to yield to the blow given it when the link strikes against

it, so as to prevent injury to the parts. The link-guide support is normally elevated by a spring M, which is arranged beneath the cross-bar G of the support, and is held thereagainst by a yoke O, secured to the under side of the car and depending therefrom. 55

The construction and arrangement of our device being thus made known, the operation of the same is thought to be obvious. 60

When it is desired to couple two draw-heads together, the coupling-link is secured in one draw-head and the two draw-heads then brought together. As the draw-heads approach, the end of the link will impinge 65 against the link-guide, and will be thereby turned upward, so that the link will be directed into the draw-head. After the link has entered the draw-head the springs L M will throw the link-guide and its support upward, so that the guide will bear against the link and hold it in the draw-head. 70

It will be seen from the foregoing description that we have provided an extremely simple device by which the link will be positively directed into the draw-head, so that the coupling will be accomplished with certainty. The construction of our device is such as to render it extremely light, and yet give it the requisite strength. 75 80

By the use of our device cars of different heights can be readily coupled together.

The operating-bar D and the lever E facilitate the uncoupling of the cars from the top and side, so that it is unnecessary for the operator to go between the cars. 85

Having thus described our invention, what we claim, and desire to secure by Letters Patent, is—

1. The combination of the yielding link-guide support and the yielding link-guide mounted on the outer end of the same, as set forth. 90

2. The combination of the link-guide support and the curved link-guide pivoted to the front end of said support, as set forth. 95

3. The combination of the yielding link-guide support, the link-guide pivoted to the front end of said support, and the spring arranged between the guide and the support, as set forth. 100

4. The combination of the link-guide sup-

port pivoted to the under side of the car, the link-guide pivoted to the front end of the support, the spring arranged between the guide and the support, the yoke secured to the car, 5 and the spring supported by said yoke and bearing against the link-guide support, as specified.

In testimony that we claim the foregoing as

our own we have hereto affixed our signatures in presence of two witnesses.

THOMAS HENRY WASH.
NATHAN ROBERT HODGE WASH.
